UNITED STATES PATENT OFFICE.

CHARLES W. HERRIN, OF KANSAS CITY, MISSOURI.

ELEVATOR MECHANISM.

Application filed February 1, 1926. Serial No. 85,255.

My invention relates to improvements in elevator mechanism for use in connection with the drilling apparatus disclosed by my copending application filed July 6, 1925, 5 Serial No. 41,660. The present invention is for the purpose of raising and lowering the sleeve carrying the bits disclosed by said copending application.

In order that the invention may be fully 10 understood, reference will now be had to the accompanying drawings, in which:

Fig. 1 is a vertical section of the apparatus with the sleeve being lowered by the elevator mechanism to active position upon the 15 drill stem.

Fig. 2 is an elevation, partly in section, of the elevator apparatus ready to release the sleeve from active engagement with the drill stem, so that said sleeve may be lifted to 20 the surface with the bits.

Fig. 3 is a view somewhat similar to Fig. 2, with the lower portion of the drilling mechanism broken away and the elevator mechanism adjusted to lift the sleeve and the 25 bits, to the surface.

Fig. 4 is an enlarged vertical section of the elevator mechanism being lowered upon the drill stem preparatory to lifting the sleeve and the bits from the well.

Fig. 5 shows the parts disclosed by Fig. 4 in the position which they assume after the sleeve and the bits have been lowered to active position and the elevator mechanism is ready to be lifted from the well.

Fig. 6 is a cross section on line 6—6 of Fig. 4.

Fig. 7 is a side elevation of a nut forming a part of the elevator mechanism.

Fig. 8 is a side elevation of an internal 40 nut which is adjustable in the nut disclosed by Fig. 7.

Fig. 9 is a side elevation of a tubular dog-carrying member which cooperates with the nuts disclosed by Figs. 7 and 8.

Fig. 10 is a plan view of the parts disclosed by Fig. 9.

Fig. 11 is a detail elevation of a plunger constituting a portion of the elevator mechanism.

Fig. 12 is a detail side elevation of a tubular element, which in practice is mounted in the upper end of the sleeve.

Referring now in detail to the various parts, 2 designates the rotary drill stem which is made up of sections united by 55 couplings 4, said sections being added from

time to time as the depth of the well is increased by the drilling mechanism.

6 designates the sleeve which is removably mounted upon the stem 2 with which it 60 is caused to rotate when in operative position, by diametrically opposed feathers 8 which fit into corresponding longitudinal grooves 10 arranged within the sleeve 6.

The sleeve 6 is provided adjacent to its 65 lower end with a pair of bits 14 adapted to interlock with a chuck 32 fixed to the lower end of the drill stem 2 for the purpose of locking the bits 14 in active position as shown by Fig. 2. As the construction and 70 operation of the drilling mechanism is the same as that disclosed by my copending application hereinbefore referred to, I do not deem it necessary to enter into a detail description of the bits 14 and the chuck 32, 75 or the manner in which they interlock and are unlocked from each other.

The upper portion of the sleeve 6 is provided with a plurality of pivotally mounted 80 internal dogs 54 adapted to engage a peripheral shoulder 56 formed on the drill stem 2 by cutting therein a tapered annular recess 58.

The upper end of the sleeve 6 has a removable cap 60 with an axial bore in which a 85 tubular element 62 has a slidable fit. The lower end of the tubular element 62 is provided with an annular clamp 64 adapted to engage over the upper ends of the dogs 54, Fig. 2, to hold them in engagement with the 90 shoulder 56 and thereby prevent the sleeve 6 from moving upwardly on the drill stem 2 when the apparatus is in drilling position.

The upper portion of the tubular element 62 is provided with spaced collars 66 and 68 95 for engagement by dogs 70 forming part of the elevator mechanism 73. The dogs 70 are pivotally mounted on a ring 72 slidably mounted within a tubular jacket 74. Independent downward movement of the ring 72 100 is limited by a pin 76, which projects inwardly from the jacket 74 into a peripheral groove 78 in said ring.

The upper portion 80 of the ring 72 is reduced to slidably fit within the lower portion of a nut 82, the sliding-movement being restricted by a pin 84 projecting from the ring 72 into a slot 86 within said nut 82. The nut 82 has a sliding fit in the jacket 74 105 and is provided at its lower margin with recesses 88 to receive the upper ends of the dogs 70 when in the position disclosed by 110

Figs. 1 and 4. The nut 82 has threaded therein an internal nut 90, which when adjusted upwardly permits the upper ends of the dogs 70 to pass inside of said nut 82 and be locked thereby in inactive position as disclosed by Fig. 5.

The nut 82 is slidably mounted upon the intermediate portion of a plunger 92, but caused to rotate therewith through the intermediacy of groove and feather connections 94. The plunger 92 has a slidable fit upon the drill stem 2 and within the ring 72, and is provided at a point above the nut 82 with a collar 96, which limits the slidable movement of the plunger 92 by contacting the top of the nut 82 or the bottom of a cap 98 threaded into the upper end of the jacket 74 and having an axial bore through which the plunger 92 slidably extends.

20 The upper portion of the plunger 92 is equipped with a tubular head 120 which is slidably mounted upon said plunger, but prevented from rotating thereon by a groove and feather connection 122. The upper end 25 of the plunger 92 has a peripheral collar 124 adapted to contact an internal shoulder 126 within the head 120 and thus prevent the latter from slipping upwardly off of the former. The collar 124 is provided with three, 30 or any other suitable number, of pivotally mounted detents 128 having tapered upper ends 130 adapted to contact an annular beveled shoulder 132 within the upper portion of the head 120. The lower ends of the detents 128 are tapered as indicated at 134 for 35 contacting an annular tapered shoulder 136 within the lower portion of the head 120. The upper end of the head 120 is provided with eyes 100 to which the lower ends of a cable 103 are attached for the purpose of 40 raising and lowering the elevator mechanism 73. The cable 103 may be controlled from the surface in the customary manner. Should the elevator mechanism or the drilling mechanism while being lowered encounter a projection on the wall of the well that 45 would check their downward movement, the elevator mechanism and the drilling mechanism can be forced downwardly by lowering the drill stem 2 until one of the couplings 4 engages the upper ends of the detents 128 which are forced into the path of said coupling 4 by the shoulder 132, which moves 50 downwardly with the head 120 as the cable 103 becomes slack due to the descent of the drilling mechanism or the elevator mechanism being checked by said obstruction. Downward pressure may then be exerted 55 upon the drill stem 2 until the obstruction is dislodged, whereupon downward movement of the plunger 92 while the head 120 is supported by the cable 103, will carry the tapered lower ends of the detents 128 into contact with the shoulder 136 and thus disengage 60 said detents 128 from the coupling 4,

so that lowering of the elevator mechanism 73 by means of the cable 103 can be resumed.

In practice when starting to drill a well the drill stem 2 is equipped with the sleeve 6 and the bits 14, the elevator mechanism being 70 omitted. As the drilling progresses and the bits 14 become dull and require sharpening, they, with the sleeve 6, are lifted to the surface by the elevator mechanism 73 which is lowered with the drill stem 2 for that 75 purpose. Before lowering the elevator mechanism the nut 82 is adjusted upwardly so that the upper ends of the recesses 88 will just clear the upper ends of the dogs 70, Figs. 1 and 4, leaving the same to move 80 freely on their pivots 71. The internal nut 90 is then adjusted to its lowermost position against the top of the ring 72 by rotating the plunger 92, to prevent the nut 82 from dropping behind the upper ends of the dogs 85 70 and locking them in inactive position as shown by Fig. 5. After the foregoing adjustments have been made the elevator mechanism 73 is lowered with the cable 103 until the jacket 74 rests upon the cap 60, which 90 is a signal to the workmen that the elevator mechanism is ready to be lifted to the surface. As the elevator mechanism 73 is lifted with the dogs 70 resting on the beveled flange 75 at the lower end of the jacket 74, 95 said flange forces the lower ends of said dogs 70 into engagement with the under side of the collar 66, Fig. 2, of the tubular element 62, which, on being lifted by the dogs 70, lifts the sleeve 6 through the intermediacy 100 of the clamp 64 which is lifted into engagement with the underside of the cap 60, Fig. 3. The upward movement of the clamp 64 frees the dogs 54 so that they can slide out of engagement with the beveled shoulder 56 105 to the position shown by Fig. 1, as the sleeve 6 moves upwardly with the elevator mechanism 73. On reaching the surface the bits 14 are removed from the sleeve 6 and resharpened or replaced by others.

110 Preparatory to again lowering the sleeve 6 and the bits 14 to drilling position, the tubular element 62 is raised until the bottom of the collar 68 passes above the hook ends 77 of the dogs 70, which are forced upwardly 115 and backwardly out of the way to the position disclosed by Fig. 5, by the beveled upper ends of the collars 66 and 68 contacting the beveled portions 70 at the lower ends of said dogs 70. After the collar 68 passes 120 above the hook ends 77 the dogs 70 move downwardly by the force of gravity and the beveled flange 75 forces the hook ends 77 against the tubular element 62 at a point beneath the collar 68, the jacket 74 being 125 supported by its cap 98 resting upon the collar 96 of the plunger 92 as shown by Figs. 1 and 4. The internal nut 90 is then screwed upwardly until it contacts with the internal flange 88 at the upper end of the nut 82, 130

by rotating the jacket 74 while the plunger 92 is held stationary. The cable 103 is then lowered with the elevator mechanism 73, the sleeve 6 and the bits 14, until the latter are properly positioned in the chuck 32. The drill stem 2 with the sleeve 6 and the elevator mechanism 73, are then simultaneously lowered until the bits 14 rest upon and are supported by the bottom of the well. The tubular element 62 and the elevator mechanism 73 continue their downward movement, permitting the beveled lower ends of the dogs 70 to engage the beveled upper reduced terminal 61 of the cap 60 which throws said dogs 70 out of engagement with the collar 68, as shown by Fig. 5. Just as the dogs 70 are disengaged from the collar 68 the jacket 74, which has an opening 79 in its lower end to receive the terminal 61, comes to rest upon the cap 60, while the plunger 92 continues its downward movement, causing its lower end to contact the collar 66 and push the tubular element 62 downwardly until its annular clamp 64 engages over the dogs 54 to hold them in locked engagement with the shoulder 56. As the plunger 92 forces the tubular element 62 downwardly the diametrically reduced portion 97 of the collar 96 impinges against the upper end of the internal nut 90, forcing the same downwardly so that it in turn will carry the nut 82 downwardly behind the upper ends of the dogs 70 and thus lock said dogs in the inactive position disclosed by Fig. 5. The elevator mechanism 73 is now ready to be lifted to the surface without the sleeve 6 as the dogs 70 are held in position by the nut 82 to clear the collars 66 and 68.

From the foregoing description, taken in connection with the drawings, it is apparent that I have provided an apparatus embodying the advantages above pointed out, and while I have shown and described the preferred construction, combination and arrangement of parts, I reserve the right to all such modifications thereof as properly fall within the spirit and scope of the invention as claimed.

Having thus described my invention, what I claim and desire to secure by Letters Patent, is:

1. In an elevator mechanism of the class described, a dog for raising and lowering drilling mechanism, a ring movable over the drill stem and upon which said dog is freely mounted, a jacket slideable longitudinally upon said ring and provided with bevel means for adjusting said dog to active position preparatory to raising said drilling mechanism, and means connected to said jacket for raising and lowering the latter.

2. In an elevator mechanism of the class described, a dog for raising and lowering drilling mechanism, a ring movable over the

drill stem and upon which said dog is freely mounted, a jacket enclosing said ring and provided with means for adjusting said dog to active position, and a member in said jacket which is vertically movable in one direction to hold the dog in inactive position and movable in a reverse direction to release said dog so that the jacket may cause said dog to engage the drill stem.

3. In an elevator mechanism of the class described, a dog for raising and lowering drilling mechanism, a ring encircling the drill stem and upon which said dog is freely mounted, a jacket enclosing said ring and provided with means for adjusting said dog to active position, a member in said jacket which is movable in one direction to hold the dog in inactive position and movable in a reverse direction to release said dog, and a plunger slidably mounted in the jacket and adapted to cause said member to hold the dog in inactive position.

4. In an elevator mechanism of the class described, a dog for raising and lowering drilling mechanism, a ring encircling the drill stem and upon which said dog is freely mounted, a jacket enclosing said ring and provided with means for adjusting said dog to active position, a member on said jacket which is movable in one direction to hold the dog in inactive position and movable in a reverse direction to release said dog, and an element adapted to be adjusted into engagement with the ring and hold said member in position to release the dog.

5. An elevator mechanism of the class described consisting of a plunger, means for raising and lowering said plunger, a jacket having limited independent movement upon said plunger, an element having limited independent movement in said jacket, dogs mounted on said element and adapted to be adjusted by said jacket into active position preparatory to raising and lowering drilling mechanism, an adjustable member in the jacket adapted to secure said dogs in inactive position, and a nut adapted to be adjusted in one direction to engage the dog carrying element and hold said adjustable member out of engagement with the dogs, or adjusted in a reverse direction to allow said adjustable member to engage and hold the dogs in inactive position.

6. An elevator mechanism of the class described consisting of dogs for raising and lowering drilling mechanism, a member carrying said dogs and having an opening for passage of the drill stem, a jacket enclosing said dog carrying member and having an opening for passage of the drill stem and provided with means for adjusting the dogs to active position preparatory to raising and lowering the drilling mechanism, a member in said jacket which is movable in one direction to hold the dogs in inactive position so

that the elevator mechanism can be lifted independently of the drilling mechanism and movable in a reverse direction to release said dogs so that they can be adjusted to active position by the jacket, a plunger having an opening for passage of the drill stem and adapted to cause the last-mentioned member to hold the dogs in inactive position, detents mounted upon said plunger for engagement with the drill stem so that the latter may be used in forcing the elevator mechanism downward, and a movable head upon said plunger for adjusting the detents to active and inactive positions.

7. In an elevator mechanism of the class described, a tubular element connected to a drilling mechanism and provided with a collar, a dog for engaging said collar to lift the drilling mechanism to the surface, a member on which said dog is mounted, and a jacket having a beveled portion which forces the dog into engagement with said collar as the elevator mechanism is lifted towards the surface.

8. In an elevator mechanism of the class described, a tubular element connected to a drilling mechanism and slidably mounted upon the drill stem, a projection at the upper portion of said element, dogs for engaging said projection and lowering the drilling mechanism into a well, a member for holding said dogs in engagement with the projection during the lowering operation, means on the drilling mechanism for disengaging the dogs from the projection after said drilling mechanism reaches the bottom of the well, and means for raising and lowering said member.

9. An elevator mechanism of the class described consisting of a tubular element connected to a drilling mechanism and provided with upper and lower projections, a jacket free to move vertically upon the drill stem, a member having limited vertical movement in said jacket, dogs carried by said member and arranged to be held by the jacket in engagement with the lower projection while lowering the drilling mechanism, which latter disengages said dogs from the projection after reaching the bottom of a well, means carried by the jacket for hold-

ing the dogs inactive while the elevator mechanism is being raised from the well independently of the drilling mechanism, and an adjustable member within the jacket for holding said means out of engagement with the dogs so that the same may be forced by the jacket into engagement with the upper projection after the elevator mechanism has been again lowered preparatory to raising the drilling mechanism.

10. In an elevator mechanism of the class described, a dog for raising and lowering drilling mechanism, a member loosely embracing the drill stem and upon which said dog is mounted, a jacket enclosing said member and provided with means for adjusting said dog to active position, a plunger loosely embracing the drill stem and extending into said jacket, detents mounted upon the plunger for engagement with the drill stem, and a movable head upon said plunger for adjusting said detents in and out of engagement with the drill stem.

11. In an elevator mechanism of the class described, a tubular element movable longitudinally upon a drill stem and provided with a peripheral projection, a plunger movable over the drill stem and adapted to press upon said projection, detents carried by said plunger and adapted to engage a coupling upon the drill stem, and a tubular head slidably mounted upon said plunger and adapted when slid in one direction to force the detents into engagement with said coupling and when slid in a reverse direction to disengage the detents from the coupling.

12. In an elevator mechanism of the class described, a tubular element movable longitudinally upon a drill stem and provided with a peripheral projection, a plunger movable over the drill stem and adapted to press upon said projection, detents carried by said plunger and adapted to engage a coupling upon the drill stem, a head slidable upon said plunger and adapted to force the detents in or out of engagement with said coupling, and means attached to said head for raising and lowering the same.

In testimony whereof I affix my signature.

CHARLES W. HERRIN.
